GAS AND AIR MIXING DEVICE

Samuel Barton Brown, Los Angeles, Calif.

Application November 25, 1935, Serial No. 51,490

3 Claims. (Cl. 48—180)

This invention relates to improvements in gas and air mixing devices for use in situations where gas and air are mixed in certain proportions preparatory to combustion as, for example, in internal combustion engines and in gas furnaces.

Among the objects of the invention are to provide an improved means for interspersing with each other a multiplicity of small streams of gas and air in such a manner as to mix the gas and air in a more intimate manner; to provide improved means to keep dirt or dust from interfering with the efficiency with which the device operates; to provide a more precise means to regulate the proportions of air and gas admitted for mixing; and to render the regulating devices more accessible and easy to operate.

Speaking specifically, one valuable feature of the invention resides in the provision of an improved arrangement of two cooperating sets of gas supply and air supply perforations, one of these sets being contained in a cylindrical piston, and the other in a cylindrical member with which said piston is adjustably combined.

Other objects, advantages and features of the invention will hereinafter appear.

Referring to the accompanying drawing, which illustrates what is at present deemed to be a preferred embodiment of the invention,

Fig. 1 is a vertical mid-section of the complete device.

Fig. 2 is a partial transverse section taken on line 2—2 of Fig. 1.

Fig. 3 is a developed vertical diagram illustrating in a conventional manner the arrangement and distribution of the gas supply apertures or foramina in and around the gas feeding tube.

Referring in detail to the drawing, the elongated structure shown is intended to be used in an upstanding position, the adjustable parts being contained within a cylindrical housing A having a body portion 5, a foraminated diametrically reduced portion or neck 6 below said body, and below said neck a lower end portion 7 which is preferably of a somewhat greater diameter than said neck. Between the portions 6 and 7 an outwardly projecting flange 8 is provided which is peripherally stepped at 9 in order to support an air distributing jacket 10. The housing A both supports and protects the parts associated therewith.

Within the three-part housing which has been described is a cylindrical floating piston B which has a head 11 carried by a neck 12, said head having a working fit within the body 5 of

the housing. Near its lower end said neck has an external peripheral flange 13 which has a working fit within the neck 6 of the housing. Below the flange 13 said neck has a thin skirt, the internal diameter of which is considerably greater than the internal diameter of the neck 12.

Above the head 11 of the floating piston there is contained within the housing A an annular chamber 15 centrally of which is located the adjustable vapor supply tube 16. The upper end portion of said tube extends through and has a working fit within a packing gland 17. Said packing gland is formed centrally upon a cap 18 which closes the top of the said chamber 15 and is removably secured in place in any suitable manner.

Air for thinning the fuel mixture is supplied through a tubular extension 19 of the jacket 10 which, by means of a pipe 20 communicates with an air cleaner, not shown, which may be of any approved conventional type. Air is thus supplied to the annular chamber 21 within said jacket. The housing body 5 and neck 6 combine to form the inner wall of said chamber 21. The foraminations 22 of the neck 6 freely admit the air to the space enclosed by said neck, but in operation air will not circulate above the flange 13 of the float, there being a dead air space 23 above said flange within the housing. Below said flange is the annular mixing chamber 23m.

A plurality of open-ended tubes 24, one of which is shown in Fig. 1, extend through the head 11 and the lower flange 13 of the floating piston, air tight fits being made where said tubes pass through said head and flange. In operation gaseous fuel is fed to the lower portion of the housing A through a fitting C which is secured to the lower end of the housing and has an intake port 25 into which is secured the fuel supply pipe 26. This gas is conducted from said fitting up through the vapor supply tube 16 to a portion of said tube which is provided with a multiplicity of outlets or foraminations 27, said outlets being obstructed internally to the extent desired by means of an adjustable shutter S, and are externally controlled by the lower inside edge 13x of the floating piston.

Suction from the manifold of an internal combustion engine, not shown, or other source, has access to the housing A through the port 28 in communication with which is shown a pipe 29. This suction simultaneously entrains air through the foramina 22 of the housing and gas through the foramina 27 of the gas supply tube 16, and

at the same time, through the tubes 24, creates suction in the upper chamber 15.

The shutter S already mentioned, may be described as a slotted cylinder, or tubular member 5 open at its lower end and having wide diametrically opposite slots 30, 30x cut in its sides between the shutter plates 31, 31x. Each of said slots extends nearly its entire length. The two shutter side plates constitute closure means and 10 are slightly unequal in width, and the same is true as to the width of the shutter slots in order to control more precisely the gas intake while the engine is idling, as will hereinafter be more fully explained. The top of said shutter is closed, 15 being furnished with a central head or enlargement 32. A bore extends through this head and within said bore is fixed a steel rod 33 by means of a pin 32x whereby said shutter is adjusted rotationally with respect to the gas supply tube 20 16 within which it has a working fit. A thin walled steel tube 34 is slipped over said rod 33 and extends from the lower end of the head 32 downward to a washer 35 at its lower end, said washer, in turn resting upon a packing gland 36 25 which prevents leakage around the rod 33.

Said tube 34 also takes the thrust of a strong compression spring 37 which is coiled around said rod and transfers it to the bottom fitting C. A thrust collar 38 at the top of said spring thrusts 30 against a round block 39 which is soldered and sweated into the upper end of the vapor supply tube 16 and forms a closure for said tube. Said thrust collar is provided with a packing gland 40 to prevent leakage around the upper end portion of the rod. At its lower end the spring 35 is coiled around and rests upon a circumferentially stepped bearing block 35b, which, in turn, rests upon the top of the shutter S.

The vapor supply tube 16 is held against rotary displacement by means of a keyway slot 41 in the lower end thereof, a plug 42 seated in a radial recess in the fitting C cooperating with said slot.

Owing to the fact that the head 11 on the upper end of the floating piston is of a greater 45 diameter than the flange 13 near the lower end of said piston, suction received through the lower port 25, presumably from an internal combustion engine, tends to lift said piston. Therefore, if the engine back-fires the pressure suddenly 50 communicated to the interior of the housing would make the piston slam down violently on its valve seat if some means were not provided to guard against this taking place. Hence a release valve 43 is secured to the cap 18, and is 55 normally held closed by a light spring 44, permitting the valve to be easily opened by inside pressure. The tension of the spring should be such as to properly control or minimize the movement of the piston B in case of engine back-fire. If said spring is too strong back-fire will slam 60 the piston down; if the spring is too weak the piston will be violently projected up against the cap 18.

Rotational adjustment of the rod 33 together 65 with the shutter S fixed thereto is obtained by means of an arm 45 which is secured near one end to the lower end of said rod, said arm having an upwardly offset portion 46 at its free end which is furnished with a set screw 47 engageable 70 with the outer surface of the tubular fitting C to maintain said arm in the adjusted position. By preference and as shown the arm 45 is secured to the rod by means of a screw 48 which seats laterally in a recess provided therefor in the rod. Said arm 45 abuts against the lower end of the

fitting C to limit the lifting action of the spring 37 upon the rod conveyed through the collar 38 and block 39 and a split nut 49 which is secured to the upper end of said rod. The bearing block 35b below the spring 37 prevents tortional action 5 of said spring from interfering with rotary adjustment of the shutter S by means of the arm 45.

Said nut 49 forms part of an auxiliary feed regulating means to regulate the feeding of minute quantities of gas to an idling engine. Said 10 nut 49 screws on to the upper end of the rod 33 and has a clamping screw 50 whereby said nut may be clamped to said rod in different adjusted positions with regard to the length of said rod thereby varying the vertical position of the vapor 15 supply tube 16 to expose more or less of the lowest row of perforations 27 below the lower end of the shutter S. Owing to the fact that the block 39 is secured to the upper end portion of said tube, when said nut is adjusted upwardly 20 it permits the spring 37 to raise said tube to the extent of such upward adjustment. When screwed down, the nut depresses the tube against the opposition of the spring.

The gas supply tube 16 is furnished with an 25 external integral collar 51 on which the floating piston P rests at the lower limit of its travel and against which the piston may strike with considerable force in case of engine back-fire. Said collar is beveled around its upper end to match 30 the beveled part 13x of the piston in order that these parts may cooperate to shut the gas off completely when they are in contact with each other.

The shock created by the piston P in falling to 35 its lowest position is successively transferred from said collar 51 to the tube 16, thence to the block 39 in the upper part of said tube, and from said block successively to the collar 38, spring 37, bearing block 35b, shutter head 32, steel tube 34, 40 and finally through the washer 35 to the fitting C at the lower end of the apparatus. The spring 37, notwithstanding its stiffness, absorbs a portion of the shock.

A removable screw plug 52 in the cap or cover 45 18 permits an opening to be made through said cap for the injection of a fluid to cleanse the chamber 15 from the products of combustion injected into said chamber by engine back-fire.

In Fig. 3 is shown a developed schematic dia- 50 gram which illustrates the arrangement of the perforations 27 in the vapor supply tube 16 through which the fuel gas emerges from said tube.

In this view the gas holes 27 are shown drilled 55 on a spiral thread with a quadruple pitch and located in the first and third vertical quadrants of the developed cylindrical gas tube 16, the quadrants of which are progressively lettered 1q, 2q, 3q and 4q, and are located on alternate threads 60 on said quadruple pitch in such a way that the holes 27 open successively one after another at an even progression when the floating piston B rises, and close in like uniform manner during 65 its fall. Since the air intake holes 22 are arranged on a single pitch drilled at uniform distances apart the result is that the ratio between the gas and the air hole areas remains constant at all the various vertical positions of the floating piston B. 70

When the shutter is being turned so as to commence opening the vertical rows of gas supply holes 27 it will not begin to open the second row of holes until all the holes of the first row have been completely opened, and the second row to 75

be opened is located in the quadrant opposite to that occupied by the first row opened.

As viewed in Fig. 2 the right hand segmental plate 31x of the shutter S is slightly wider than the left plate 31 thereof, and the side opening 30x is slightly wider than the opening 30 at the opposite side of the shutter. Said shutter side plates are so arranged as to progressively open vertical rows of the gas holes 27 as the shutter is rotationally adjusted by turning the arm 45 at the lower end of the device. It is owing to this difference in the widths of the side openings of the shutter that only one row at a time of the holes 27 can be opened or closed. The shutter may be so adjusted and set as to open or expose only a fraction of a row of holes for minute regulation of the gas flow. This shutter adjustment controls the gas-air ratio thus giving the mixture delivered the desired degree of fuel richness.

20 The shutter may be turned to a position wherein the side plates thereof completely cover the perforated areas of the gas tube and thereby completely shut off the gas supply; or it may be turned to a position wherein its side plates come 25 opposite to the imperforate portions of the tube and uncover all its gas feeding holes or perforations.

The skirt 14 at the lower end of the floating piston B, is shown in full lines in Fig. 1 at the upper part of its travel. In operation said skirt usually occupies a position wherein it compels all the air entering through the holes 22 to be deflected downwardly before it mingles with the gas coming out of the perforations 27. The skirt 14 keeps the dust and other foreign matter drawn in with the air from clogging the sliding bearing between the tube 16 and said piston, and also keeps the dirt and dust from clogging the gas outlet perforations 27.

40 In the operation of the device as a fuel supply means for an internal combustion engine the lever 45 at the base of the device should generally be set to maintain a four to eight inches water column pressure beneath the floating piston B. After said lever has been set in the proper position it is not usually necessary to vary the adjustment, which can be made permanent by screwing down the lever set screw 47.

The floating piston B automatically rises and falls according to the speed and load of the engine. As said piston goes up it opens and as it goes down it closes the gas and air holes in the same proportion, acting on the principle of a duplex multiple orifice meter.

55 When the engine is stopped, the weight of the piston B brings it down to the shoulder afforded on the gas tube 16 by the collar 51 thereof, thus automatically shutting off the gas to prevent it from entering the intake manifold and flooding the engine.

When the engine and magneto are in good condition the engine should start with a quarter turn of the crank, or the striking of one impulse on the magneto.

65 The regulation of the nut 49 at the top of the device for feeding idling engines has already been described.

During the operation of the device as a means for supplying fuel gas and air mixtures to the internal combustion engine of an automotive vehicle, when the operator desires to increase speed he opens more widely the throttle (not shown) thus causing an increase in the quantity of fuel mixture withdrawn through the outlet 28 which 70 leads to the manifold of the engine. This will

cause the floating piston B to rise (owing to the fact that the upper surface of the piston head 11 is of a greater area than the portion of the opposite end of the piston which is affected by the suction) to a point where the pressure drop through 5 the air holes 22 is constant and equals the weight of the piston. Conversely a closing movement of the throttle will lower the suction and cause less fuel to be withdrawn, and allow the piston to descend till the device equalizes itself at a lower 10 feed of fuel.

It is seen that the piston automatically controls the total port opening afforded by the air intake opening 22 and the fuel feed openings 27 in such a manner as to maintain correct amounts 15 of air and gas in proportion to the amount of mixture flowing out through the delivery port 28.

In practice it is found that the fuel used must be transmitted to the fuel feed conduit 26 in a more or less dry and vaporized form and not in 20 the form of liquid particles.

Owing to the fact that a constant air and gas ratio is automatically obtained over a full range of operation at different speeds, it is possible to economize fuel and obtain maximum efficiency 25 from given quantities of fuel. It has been found that using the device in automotive service results in a mileage increase of from ten to twenty-five percent for railway motor coaches, this saving being effected by reason of the precise fuel feed 30 adjustment obtainable in regard to the required gas and air ratios.

I claim:

1. In a gas and air mixing device, a casing, a vapor supply tube mounted therein in a non-rotatable longitudinally adjustable manner, said tube having foraminated fuel feeding areas, a shutter having a working fit within said tube, a turnable rod mounted axially within said tube, said tube having a block fixed within one end portion thereof through which said rod turnably projects with a fluid tight fit, said shutter being fixed to said rod within said tube independently of said block, a spring coiled around said rod between said shutter and block and tending to move said rod 40 longitudinally away from said block, the opposite end portion of said rod projecting through said casing and having its projecting portion furnished with means to rotationally adjust the rod to vary the delivery of vapor fuel through the 45 aforementioned foraminated areas of said tube, an adjusting nut mounted upon the end portion of said rod which projects beyond said block, said nut cooperating with said spring to vary the longitudinal position of said tube with relation to 50 said shutter thereby to effect an auxiliary fuel feed adjustment, and means to mingle air with the regulated flow of gaseous fuel passing out from the foraminated portion of said tube, said air mingling means including a floating member 55 operable by engine suction to control fuel passages, and said tube extending axially through said member with a gas tight working fit.

2. In a gas and air mixing device, a housing, a gas supply tube mounted therein and having outlet perforations, said housing having air inlet perforations in a radially spaced relation to said gas outlet perforations, there being an annular mixing chamber between the perforated portions of said tube and housing, a piston mounted externally upon said tube with a working fit and having a working fit internally of said housing, to control both the gas and air supply, said piston having a skirt portion consisting of a tubular shell 70 spaced radially outward around said tube to ar- 75

rest solid matter and spaced radially outward around said tube to arrest solid matter and to deflect air entering the perforated portion of said housing towards an end portion of said mixing chamber as it mingles with the gas, said skirt being located below said internal working fit of said piston, and conduit means to convey the mingled gas and air from said mixing chamber.

3. In a gas and air mixing device, a casing, a longitudinally adjustable vapor supply tube mounted in said casing and having fuel feeding openings, a shutter within said tube, a rod to which said shutter is fastened, said rod extending axially through said tube, said tube having a closure fixed within one end thereof through

which said rod projects, a compression spring coiled around said rod and tending to move said closure away from said shutter, a tube to aid in taking the thrust of said spring, one end of said tube abutting against said shutter in opposition to said spring, a support being provided for the opposite end of said tube, means externally engaging said closure to regulate the longitudinal position of said tube in opposition to said spring thereby to cause a relative longitudinal fuel-vaporizing adjustment between said shutter and tube, and means to mingle air with the regulated flow of gaseous fuel passing out from the aforementioned fuel feeding openings of said tube.

SAMUEL BARTON BROWN. 15
